UNITED STATES PATENT OFFICE.

DANIEL J. McDEVITT, OF PHILADELPHIA, PENNSYLVANIA.

MILL NUT.

Application filed November 26, 1926. Serial No. 150,940.

My invention relates to mill nuts associated with the spools of spinning or twisting frames for silk, cotton, etc. In this type of spinning machine there are usually a great number of spindles employed; each spindle requires a mill nut, and, due to the frequency with which the spools are placed upon and removed from the spindles, the mill nuts, being formed from a relatively soft wood, are quickly worn out and must be replaced with new ones.

In the course of operation, mill nuts are very frequently, due to their worn out condition, accidentally displaced or removed from their spindles while in operation, thereby necessitating a great loss in time and expense.

The object of my invention therefore resides in the production of a mill nut that is formed of aluminum or any other material having a relatively hard wearing surface. The scope of my invention extends to whatever constructions or compositions may be defined by or included within the terms or language of the appended claim.

In the drawings:

Figure 1 is a side elevation of a mill nut illustrating it in its assembled position with the spindle, bobbin and drop arm flyer;

Figure 2 is a view in perspective of the mill nut, and

Figure 3 is a longitudinal sectional view thereof.

As is well known to those familiar with the art, the mill nut, generally designated at 10, has a bore 11 adapted to fit over the upper end of a spindle 12 for the purpose of retaining the drop arm flyer 13 in position immediately above the bobbin 14. The spindles 12 are of steel and have a slightly tapered upper end for extension into the mill nut bore 11 and these mill nuts are frictionally engaged with the stem. Through rotation of the spindle, oil is caused to travel upwardly on the stem and comes in contact

with the mill nut, with the result that the nut has a tendency to swell and burst where formed of wood. Furthermore, as these mill nuts, unless firmly engaged with the spindle, are likely to fly off during operation, causing disarrangement and a loss of time, they are generally very forcibly applied, with the result that they are very often split without this split becoming noticeable.

In accordance with my invention, I provide a mill nut formed of moldable material which, while readily soft so that it will not mar or damage the upper end of the spindle, is capable of taking a high polish, so that no damage will result to a worker applying or removing the same during operation of the machine. The material employed must, to be effective, be sufficiently dense to be non-absorbent, as otherwise it will collect the oil arising upon the spindle and become extremely difficult to handle. It must also be light, as otherwise the additional weight at the upper end of the spindle would, unless the spindle was absolutely truly centered, have a tendency to cause "whipping" of the same and rapidly destroy the spindle. Furthermore, during this "whipping", the nut might fly from the spindle and strike and damage either an attendant or some of the delicate portions of the machine. Materials having the qualifications above noted are aluminum and the composition commonly known in the trades as bakelite and analogous substances.

What I claim as new, and desire to secure by Letters Patent is:

As an article of manufacture, a mill nut for use upon bobbin spindles consisting of a moldable material relatively soft as regards the bobbin spindle while capable of taking a smooth finish and sufficiently dense to be substantially non-absorbent to oil, said material having a specific gravity not materially exceeding that of aluminum.

DANIEL J. McDEVITT.
